REFRIGERATOR CAR STRUCTURE

Edgar E. Schlesinger, Chicago, Ill., assignor to
 Standard Railway Equipment Manufacturing
 Company, Chicago, Ill., a corporation of Dela-
 ware

Application July 20, 1938, Serial No. 220,226

6 Claims. (Cl. 105—411)

This invention relates to refrigerator cars used to transport perishable commodities and more particularly to cars having a refrigerant container in each end of the car. The refrigerant containers are separated from the lading compartment by bulkheads rigidly secured to the car structure. The bulkheads must have sufficient strength to resist the impact of the lading when the car starts or stops suddenly.

Bulkheads are usually supported by a series of vertically disposed posts. It has been common practice to attach said posts rigidly to the roof structure and to the floor. Disadvantages of this construction are that it obstructs the passage of air beneath the bulkhead and that the connection of the bulkhead posts to the floor provides a source of leakage into the insulation, consequently, a new type of bulkhead post has been developed recently. It is connected, as formerly, to the roof but has an angularly disposed brace projecting from its lower end. The brace extends under the ice grate and is attached to the end wall of the car above the end sill, thus eliminating the connection at the floor. It is apparent, then, that since the lading thrust is usually concentrated at the lower part of the bulkhead, said thrust must be resisted by the end wall of the car.

The end wall of a refrigerator car, as commonly constructed, derives its strength from a metallic sheet formed with horizontal corrugations extending effectively between the corner posts of the car. The present trend in railway car construction is toward lighter weights and a corresponding decrease in rigidity, while the latest type of bulkhead tends to increase the thrust on the walls of the car. This thrust is more or less localized at one or two corrugations near the bottom of the corrugated end sheet.

It is an object of this invention to reinforce the end of a car against the bulkhead thrust by providing an auxiliary beam upon which said bulkhead thrust is imposed. It is a further object to form said beam to conform substantially to the contour of the corrugations and to attach the beam independently of the corrugated sheet. Said beam is not secured to the corrugated sheet because it is desired not to impair the natural resilience of said sheet.

Another object of the invention is to attach the beam to the side sills of the car, thus diverting the bulkhead thrust from the end of the car to the more rigid underframe.

A further object of the invention is to provide gussets associated with the reinforcing beam and attached to the side sills and corner posts of the car. This not only provides a rigid attachment for the beam, but also reinforces the corner construction of the car.

It is another object of the invention to posi-

tion the reinforcing beam substantially within a corrugation of the end sheet so as not to impair the insulating efficiency of the end wall or increase its overall thickness.

5 Another object is to attach said beam to the end sill of the car to further facilitate transmitting the bulkhead thrust to the underframe of the car.

It is a further object to provide the compressive edge of said beam with a flange to increase its strength as a column and, therefore, increase its overall efficiency.

In the drawings:

Fig. 1 is a partial end elevation of a refrigerator car embodying my invention.

Fig. 2 is a fragmentary section on line 2—2 of Fig. 1, some of the parts having been omitted to show more clearly the construction and attachment of the beam.

Fig. 3 is a section on line 3—3 of Fig. 2.

Fig. 4 is a section on line 4—4 of Fig. 2.

Figs. 5 and 6 show modified constructions.

The end sill 2 and the side sills 3 are secured together by the rivets 4. The corner posts 5 are preferably of W-section having flanges 6—7 and reflanges 8—9. The end wall of the car comprises a metallic sheet 10 formed with a plurality of horizontally disposed major corrugations 11 and preferably with minor corrugations 12 between the corrugations 11 and near the ends thereof. The sheet 10 is secured at its edges 13 to corner portions 14 preferably by welding. The corner portions 14 are formed with corrugations 15 which engage the corrugations 11—12 in the sheet 10. The corrugations 15 merge into a plane adjacent the opposite edge 16 of the corner portion 14. The reflare 9 of the corner post 5, the edge 16 of the corner portion 14, the side sheathing 17 and the vertical leg of the side sill 3 are secured together, while the reflare 8 of the corner posts, the end sheet 10, the corner portion 14 and the vertical leg of the end sill 2 are also secured together to form a strong box construction at the corner of the car.

40 The bulkhead 20 is supported by bulkhead posts 21 secured at their upper ends to the roof of the car and having braces 22 projecting from the lower ends thereof. Wooden stringers 23—24 are held in place by the bolts 25 and clips 26. Brackets 27 are secured by bolts 28—29 to the stringers 23, which are within the corrugations 11. The braces 22 are secured to the brackets 27 by the bolts 30 and a spreader block 31 is provided to distribute the thrust from the braces

55 22. Ice grates 35 are supported at one end by the brackets 27 and at the other end by the bulkhead posts 21. The screen 36 provides a passage 37 for air movement. Other parts of the car shown in Fig. 3 are refrigerant space 40, lading compartment 41, floor rack 42, floor 43, sub-floor 44, drip

pan 45, end lining 46 and insulation 47. The parts of the car are proportioned so that the portion of the insulation 47 disposed between the stringer 24 and spreader block 31 is compressed to a substantially incompressible mass.

The reinforcement 50 is pressed preferably from a metallic sheet of heavier gauge than the end sheet 10. The reinforcement 50 has a beam portion 51 conforming substantially to the contour of the corrugation 11. The beam 51 is positioned within the corrugation 11 and is in contact therewith throughout substantially its entire length. The reinforcement 50 has formed integral with it a lower part 52 secured to the end sill 2 by the rivets 53. Gussets 54 are preferably formed integral with the reinforcement 50 at each end thereof. The gussets 54 are secured by the rivets 55 to the flanges 6 of the corner posts 5 and are provided with flanges 56 which are secured by the rivets 4-57 to the end sill 2 and side sills 3. The beam 51 is not secured to the sheet 10 because it is desired not to decrease the resilience of the sheet 10.

Fig. 5 shows a construction in which a flange 65 is formed on the upper edge of the reinforcement 50. When a thrust occurs against the bulkhead 20 the thrust is transmitted by the braces 22 to the beam 51. Since the tendency of the thrust is to bow the beam 51 outwardly the inner side of said beam is in compression. The flange 65 stiffens the compressive edge against buckling and, therefore, strengthens the beam as a whole.

Fig. 6 shows a modification in which both the upper and lower edges of the reinforcement 70 are free so that the resilience of the said reinforcement is not impaired by attachment to the rigid end sill 2.

It should be emphasized that the reinforcement 50 is not a common strengthening member secured to the sheet 10. It is a beam having a contour substantially similar to the contour of the sheet corrugation 11 so that their deflections will be proportional. Furthermore, the natural resilience of the sheet 10 is left unimpaired by attaching the reinforcement 50 separately from the sheet 10. A thrust upon the bulkhead 20 is, therefore, transmitted by the braces 22 through the spreader block 31 to the reinforcement 50 and thence by the gussets 54 to the underframe comprising side sills 3 and end sill 2.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having a longitudinally extending sill, spaced apart substantially vertical corner posts, a horizontally corrugated end wall sheet extending therebetween and secured thereto, spaced apart side walls, a bulkhead extending between said side walls in spaced relation to the end wall sheet to provide a refrigerant chamber therebetween in combination with a substantially horizontal beam nesting in a corrugation of the end wall sheet, means to secure said beam to said sill, a brace secured to said bulkhead, and means interposed between said brace and said sill to transmit horizontal forces from said brace to said beam.

2. In a refrigerator car having corner posts, a

horizontally corrugated end wall sheet extending between and secured to said posts, side sills, side walls, a bulkhead extending between said side walls in spaced relation to the end wall sheet to provide a refrigerating chamber, in combination with a beam positioned substantially within the lowermost corrugation of the corrugated end wall sheet, gussets securing the ends of the beam to the side sills, and a brace secured to said bulkhead and means interposed between said brace and said beam to transmit horizontal forces imposed upon said bulkhead to said beam.

3. In a refrigerator car having an end sill, corner posts, a horizontally corrugated end wall sheet extending between and secured to said side posts, side sills, side walls, a bulkhead extending between said side walls in spaced relation to the end wall sheet to provide a refrigerating chamber, in combination with a beam positioned substantially within one of the corrugations of the corrugated end wall sheet and having a part secured to said end sill, means to secure the ends of said beam to the side sills, a brace secured to said bulkhead, and means interposed between said brace and said beam to transmit horizontal forces imposed upon said bulkhead to said beam and said end sill.

4. In a refrigerator car having corner posts, a horizontally corrugated end wall sheet extending between and secured to said posts, side sills, side walls, a bulkhead extending between said side walls in spaced relation to the end wall sheet to provide a refrigerating chamber, in combination with a beam positioned substantially within one of the corrugations of the corrugated end wall sheet, gussets securing the ends of the beam to the side sills, a brace secured to said bulkhead, and means interposed between said brace and said beam to transmit horizontal forces imposed upon said bulkhead to said beam, said gussets being also secured to said posts so as to stiffen the corner of the car.

5. In a refrigerator car having corner posts, a horizontally corrugated end wall sheet extending between and secured to said posts, side walls, a bulkhead extending between said side walls in spaced relation to the end wall sheet to provide a refrigerating chamber, in combination with a beam positioned substantially within one of the corrugations of the corrugated end wall sheet but free to function as a beam independently thereof, gussets securing the ends of the beam to the side walls independently of the corrugated end wall sheet, a brace secured to said bulkhead, and means interposed between said brace and said beam to transmit horizontal forces imposed upon said bulkhead to said beam.

6. In a refrigerator car having spaced apart substantially vertical corner posts, a horizontally corrugated end wall sheet extending therebetween and secured thereto, spaced apart side walls, a bulkhead extending between said side walls in spaced relation to the end wall sheet to provide a refrigerant chamber therebetween in combination with a substantially horizontal beam nesting in a corrugation of the end wall sheets, means to secure said beam to the car structure, a brace secured to said bulkhead, and means interposed between said brace and said beam to transmit horizontal forces from said brace to said beam.

EDGAR E. SCHLESINGER.
